UNITED STATES PATENT OFFICE.

CHARLES ROY PLACE, OF WILMINGTON, DELAWARE.

DESIGN FOR A HAT.

56,990.

Specification for Design.

Patented Jan. 25, 1921.

Application filed May 26, 1920. Serial No. 384,472. Term of patent 3½ years.

To all whom it may concern:

Be it known that I, CHARLES ROY PLACE, a subject of the King of England, and a resident of Wilmington, in the county of New Castle and State of Delaware, United States of America, have invented a new, original, and ornamental Design for a Woman's Hat, of which the following is a specification, reference being had to the accompanying drawing, forming part thereof.

The figure is a perspective view of the hat, showing my new design.

I claim:

The ornamental design for a hat as shown.

CHARLES ROY PLACE.
